JOHN F. MACNIDER, JOHN A. MACNIDER, AND FRANK J. WEISS, OF CHICAGO, AND HARRY J. JACKSON, OF WINNETKA, ILLINOIS.

COLLAPSIBLE BOX.

Application filed December 11, 1925. Serial No. 74,852.

Our invention relates to certain novel improvements in collapsible boxes and has for its principal object the production of an article of this character wherein provision is 5 made for folding the box in a flat compact condition to facilitate return of the same to the shipper.

A further object of the invention is the 10 production of an article of this character wherein the panels of the box can be expeditiously removed to facilitate folding the box in a flat compact condition.

A further object of the invention is the 15 production of a box of this character which can be expeditiously and readily distended in position to receive articles to be shipped therein.

Other objects will appear hereinafter.

The invention consists in the novel combination and arrangement of parts to be 20 hereinafter described and claimed.

The invention will be best understood by 25 reference to the accompanying drawings showing the preferred form of construction and in which:

Fig. 1 is a typical end elevational view of the invention,

Fig. 2 is a sectional view of the same taken substantially on line 2—2 of Fig. 1,

Fig. 3 is a vertical cross sectional view of the same,

Fig. 4 is a side elevational view of the invention illustrating the box with the panels and cover thereof removed therefrom,

Fig. 5 is a top plan view of the invention illustrating the box with the cover removed therefrom.

Throughout the several views illustrated in the drawings similar reference characters 40 are used to indicate similar parts.

In attaining the various objects of the invention, a box is provided with end frames 10 and 11, each of which include angular corner pieces 10' and 11' having opposite 45 longitudinal edge portions bent upon themselves providing opposite open longitudinal recesses 12 arranged and adapted to removably accommodate end panels 13 and 14 formed of such material as will best serve 50 the purpose. The inner flanges 15 of these bent edge portions have their lower end portions cut away as at 16 for reasons herein-

after set forth. Top connecting strips constitute the top frame members of the end frames as indicated at 16' and are attached 55 to the flanges 15 as at 17 in a manner well known in the art and are provided with end holes 18 in registration with holes 19 formed in the upper ends of the inner flanges 15 and the outer flanges 20 for reasons hereinafter 60 more fully understood. The end frames are pivotally connected as at 21 to a bottom frame 22. By pivotally connecting the end frames to the bottom frame the end frames can be folded upon the bottom frame as 65 illustrated in the dotted lines (Fig. 4). This bottom frame includes side pieces 23 and end pieces 24 formed angularly in cross section. The side pieces 23 have their opposite corresponding longitudinal edge portions 70 bent back upon themselves to provide longitudinal recesses 25 for the accommodation of the longitudinal edge portions of a bottom panel 25' and arranged in spaced relation with outer longitudinal recesses 26 for the 75 accommodation of the longitudinal edges of side panels 27 having their end portions slidably received by similar recesses 28 provided outwardly of the recesses 12 of the corner pieces. The end pieces 24 have their longitudinal portions cut away to provide a longitudinal slot 28' through which the bottom panel 25' is inserted to slidably engage the recesses 25 when mounted in position.

It will be noted that the outer flanges 20 85 of the corner pieces 11' extend downwardly to a point obstructing passage through the slot preventing self displacement of the bottom panel, and that to insert the bottom panel it is necessary to partially fold the end frame 11 so as to bring these obstructing end portions from obstructing position with respect to the slot. In this position of the end frame 11 the panel can be expeditiously inserted with its longitudinal edges confined in the recesses 25. After insertion of this panel the end frame 11 is distended to its extreme vertical position with the obstructing end portions in obstructing position with respect to the slot.

The bottom frame 22 has its lower longitudinal edge portion 29 bent upon itself to provide an inner longitudinal recess 29' for the accommodation of the end portion 30 of

the bottom panel. This bent portion is spaced from the flange 31 providing a longitudinal recess 32 for the reception and accommodation of the lower edge portion 33 of the end panel 14.

The box structure further includes a removable cover 34 comprising a frame including side frame members 35 angular in cross section with the longitudinal edges 37 bent upon themselves to provide longitudinal recesses 38 for the reception and accommodation of the longitudinal edge portions 39 of a top panel 40. This frame further includes end frame members 36 and 36' also angular in cross section. The end frame member 36 has its longitudinal edges 37 bent upon itself to provide a longitudinal recess 38' for the accommodation and reception of the end edge portion 39' of the top panel. This end frame member 36 further defines a longitudinal recess 41 outwardly of the recess 38' for the accommodation of the upper edge portion 42 of the end panel 14. The other end frame member 36' has an upper longitudinal portion of its side flange 43 cut away to provide a longitudinal slot 44 through which the top panel 40 is inserted to be slidably received by the recesses 38; and the recess 38'. It is important to note that the upper edge portion 45 of the end panel 13 projects upwardly in obstructing position with respect to the slot 44 serving to prevent self-displacement of the top panel and that upper end portion of the flanges 20 also extends upwardly in obstructing position with this slot to prevent unauthorized withdrawal of this top panel, and to retain the cover panel in position until the cover is removed from the box structure.

The end frame members 36 and 36' have apertures 46 formed therein in registration with the openings 19 for the insertion of suitable securing means. This securing means is not disclosed nor described in this application because it does not in itself constitute a part of the present invention.

From the foregoing description it is manifest that as long as the cover is in position the panels cannot be removed. This results from the fact that the upper flanges 37 of the longitudinal frame members of the cover extend in obstructing position with respect to the recesses slidably receiving the side and end panels of the box structure. This novel construction serves to make our shipping box, to a great extent, theft-proof.

Among the other advantageous features of the invention is the novel arrangement for retaining the bottom panel in place. This results from the fact that portions of the flanges of the corner pieces of the end frame 11 project downwardly in obstructing position with respect to the slot through which this panel is inserted to be slidably

received by the longitudinal recesses formed in the bottom frame.

In assembling the box structure in distended position the end panel 14 is mounted in its respective recesses after which the end frame 11 is pivoted about its pivots to remove the obstructing flange portions from obstructing the longitudinal recesses of the bottom frame to permit insertion of the bottom panel. After the bottom panel has been mounted in its respective position this end frame is distended to its extreme vertical position at which time the end panel 13 is mounted in its respective recesses. The side panels are now inserted in their respective recesses and after this has been accomplished and contents packed in the box thus far assembled the cover is mounted and secured in its proper position relative to the box structure after the top panel thereof has been inserted through the slot 44 into the longitudinal recesses of the cover.

While we have shown and described the preferred form of our invention, it will be apparent that various changes and alterations in the same may be carried out during manufacture without departing from the spirit of the invention or the scope of the appended claims.

Having thus set forth our invention, what we claim as new and useful is:

1. A box structure including end frame members, end panels slidably received by the end frame members, a bottom frame having inwardly extending flanges, a panel slidably received by the bottom frame, side panels slidably received by the end frame members and supported by the inwardly extending flanges, a cover frame having longitudinally extending recesses formed thereon for the accommodation of the upper edge portion of the side panels and having other longitudinally extending recesses formed adjacent said first mentioned recesses and having portions preventing withdrawal of the side and end panels, and a panel slidably received by said other recesses.

2. A box structure including a bottom frame having recesses formed thereon, a bottom panel having portions removably engaging the recesses, end frame members having a slot formed in one of the members, portions formed on one of the end frame members obstructing said recesses preventing withdrawal of the bottom panel, side panels slidably received by the end frame members, a cover frame, a cover panel insertable through the slot and slidably received by the cover frame, and end panels slidably received by the end frame members with one of the end panels obstructing the slot of the end frame.

3. A box structure including end frame members, end panels slidably received by

- the end frame members, a bottom frame having inwardly extending flanges and pivotally carrying the end frame members, a panel slidably received by the bottom frame
- 5 member, side panels slidably received by the end frame members and supported by the inwardly extending flanges, a cover frame, and a panel slidably received by the cover frame.
- 10 4. A box structure including a bottom frame having longitudinally extending recesses formed therein, a bottom panel mounted in the recesses, end walls pivotally carried by the bottom frame, one of said end walls having portions formed adjacent its lower end obstructing said recesses preventing withdrawal of the bottom panel, and side panel members carried by the end walls and supported by the bottom frame.
- 15 5. A collapsible box including a bottom frame having longitudinally extending recesses formed on opposite longitudinal sides thereof and recesses formed adjacent the longitudinally extending recesses, a bottom panel slidably received by the longitudinally extending recesses, end frames having longitudinally extending recesses and other recesses adjacent the longitudinally extending recesses pivotally carried by the bottom frame with one of the end frames provided with a longitudinally extending recess for the reception of an end portion of the bottom panel, end panels slidably received by the longitudinally extending recesses formed thereon and other recesses adjacent the longitudinally extending recesses for the reception of the top edge portions of the end panels and having a longitudinally extending slot formed in one end thereof, and a cover panel insertable through the slot and 80 slidably received by the longitudinal recesses of the cover frame.
- 20 6. A collapsible box including a bottom frame having longitudinally extending recesses formed on opposite longitudinal sides thereof and recesses formed adjacent the longitudinally extending recesses, a bottom panel slidably received by the longitudinally extending recesses, end frames having longitudinally extending recesses and other recesses adjacent the longitudinally extending recesses pivotally carried by the bottom frame with one of the end frames provided with a longitudinally extending recess for the reception of the end portion of the bottom panel, end panels slidably received by the longitudinally extending recesses in the end frames, side panels slidably received by the other recesses of the end frames and supported by the bottom frame, and a cover having portions obstructing the recesses of the end frames preventing withdrawal of the panels therefrom.
- 25 7. A collapsible box including a bottom frame defining longitudinally extending recesses on three sides thereof and other recesses adjacent the longitudinally extending recesses, and having an end portion provided with a slot, a bottom panel insertable through the slot and slidably received by the longitudinally extending recesses, end frames having longitudinally extending recesses formed thereon and other recesses adjacent the longitudinally extending recesses pivotally carried by the bottom frame, end panels slidably received by the first mentioned longitudinally extending recesses of the end frame, side panels slidably received by the other recesses of the end frames and supported by the bottom frame, and a cover having portions obstructing the recesses of the end frames preventing withdrawal of the panels therefrom.
- 30 8. A collapsible box including a bottom frame defining longitudinally extending recesses on three sides thereof and other recesses adjacent the longitudinally extending recesses and having an end portion provided with a slot, a bottom panel insertable through the slot and slidably received by the longitudinally extending recesses, end frames having longitudinally extending recesses formed thereon and other recesses adjacent the longitudinally extending recesses pivotally carried by the bottom frame, end panels slidably received by the first mentioned longitudinally extending recesses of the end frame, side panels slidably received by the other recesses of the end frames and supported by the bottom frame, and a cover having portions obstructing the recesses of the end frames preventing withdrawal of the panels therefrom.
- 35 9. A collapsible box including a bottom frame defining longitudinally extending recesses on three sides thereof and other recesses adjacent the longitudinally extending recesses and having an end portion provided with a slot, a bottom panel insertable through the slot and slidably received by the longitudinally extending recesses, end frames having longitudinally extending recesses formed thereon and other recesses adjacent the longitudinally extending recesses pivotally carried by the bottom frame, one of said end panels having a portion obstructing insertion through the slot, and panels slidably received by the first mentioned longitudinally extending recesses of the end frame, side panels slidably received by the other recesses of the end frame and supported by
- 40
- 45
- 50
- 55
- 60
- 65

the bottom frame, a cover frame having longitudinally extending recesses formed on three sides thereof and other recesses adjacent the longitudinally extending recesses, by the longitudinally extending recesses of 10 the cover frame.

In testimony whereof, we affix our signatures.

5. for the accommodation of the upper edge portions of the side and end panels and having a longitudinally extending slot formed in one end thereof, and a cover panel insertable through the slot and slidably received
